UNITED STATES PATENT OFFICE.

JOSEPH A. STEINMETZ, OF PHILADELPHIA, PENNSYLVANIA.

GRIPPING MEMBER FOR CYLINDERS.

Application filed September 22, 1923. Serial No. 664,287.

My invention relates to cylinders used for holding ammonia, acetylene and other gases, and particularly relates to cylinders of the seamless drawn steel type, having an integral head, or bottom end, formed with rounded surfaces.

The object of my invention is to provide means upon the integral head of the cylinder adapted for gripping the cylinder by hand or by hoist hooks; and a further object is to provide various forms of gripping means adapted for carrying out my invention and also to construct the gripping means so that they will form a broad and firm base for supporting the cylinders in a vertical position.

Heretofore it has been very difficult to handle a cylinder having a rounded drawn head, as it was impossible to find a place to get a hand hold or to secure a hoist hook.

Some forms of cylinders are made of tubing welded lengthwise of the cylinders and the heads are inset. These cylinders have the advantage of being readily handled. The seamless drawn cylinders now in general use have one head formed integral with the body and the opposite end formed with a separate inset head, secured in a manner well known in the art. My invention provides a gripping member which is secured to the integral head of the cylinder so that it may be readily handled.

Referring to the accompanying drawing, Fig. 1, is a central longitudinal section through a seamless drawn cylinder, showing my improved gripping member secured thereto and engaged by hoist hooks; Fig. 2, is an end view of Fig. 1, the hoist hooks being omitted; Figs. 3 to 7, are longitudinal sectional views of a portion of a cylinder, embodying various forms of gripping members; Fig. 8, is an end view of Fig. 7; Fig. 9 is a sectional view of the end of a cylinder showing a still different type of gripping member; Fig. 10, is an end view of Fig. 9; Fig. 11, is a sectional view of one end of a cylinder showing a still different type of gripping member; Fig. 12, is an end view of Fig. 11; Fig. 13, is a sectional view of the end of a cylinder showing a still different form of gripping member; Fig. 14, is an end view of Fig. 13; and Figs. 15 to 19, are sectional views of portions of cylinders showing still different forms of gripping members.

In the accompanying drawings in which

like reference characters refer to like parts, 1 represents the body of a seamless drawn cylinder having an integral head, or base 2, formed upon the cylindrical body 1. The 60 opposite head to top 3 is inset and secured to the body 1. Said head 3 forms an outwardly projecting flange which provides means for readily gripping the cylinder by hand, or by a hook 5, of the hoist 6. The 65 opposite end having the drawn head 2 presents rounded surfaces which will not permit a hook to be attached and also making it difficult to lift this end of the cylinder by hand.

My invention consists of providing a gripping member, such as shown at 8, Fig. 1, which member forms a means for readily attaching the hook 7, of the hoist, and which also forms a hand grip for lifting 75 the rounded end of the cylinder.

The gripping member 8, shown in Fig. 1, is constructed with a hemispherical body 9, adapted to fit into the concaved portion of the drawn head 2 of the cylinder. The 80 gripping member 8 also has an annular flange 10, projecting inwardly, thus providing means for securing the hook 7. The body 9 of the member 8 is secured to the cylinder head 2 by spot welding at the 85 points 12, or by electric welding.

The form of gripping member 14, shown in Fig. 3, consists of an annular collar 15, having an inwardly projecting flange 16, secured by welding at the points 17, in the 90 manner above described.

Fig. 4, illustrates a gripping member 20, consisting of a flat ring having its outer edge attached to the head 2 by welding at the points 21.

Fig. 5, illustrates a form of gripping member consisting of a ring 23, of square cross-section, which is secured to the cylinder head as above described.

Fig. 6, shows a gripping member consisting of a ring 25 of circular cross-section, secured to the cylinder head by welding.

Figs. 7 and 8, illustrate a gripping member formed of a bar 26, having its ends welded to the head of the cylinder.

Figs. 9 and 10, illustrate a form of gripping member consisting of a link, or elliptical ring 28, secured to the head 2 in a plane extending parallel with the longitudinal axis of the cylinder.

A gripping member 30 is shown in Figs. 11 and 12, in the form of a cross-bar having

its ends secured to the head 2 and a brace bar 31 is secured between the head 2 and the bar 30, in line with the longitudinal axis of the cylinder.

5 Figs. 13 and 14 illustrate a gripping member consisting of cross-bars 32 and 33 joined together centrally and having their ends welded to the head 2.

10 The gripping member 35, shown in Fig. 15, consists of a collar having a cylindrical portion 36 adapted to fit over the end of the cylinder 1 and which is welded to the cylinder at the points 37. A conical flange 38 forms part of the collar 36. Said flange 15 38 extends inwardly and also extends beyond the head 2 a sufficient distance to form a gripping member.

Fig. 16, illustrates a gripping member 40, 20 consisting of a collar having an annular concaved portion 41 adapted to receive the rounded surface of the head 2. Said collar 40 is also provided with a flange 42 which is of conical formation and forms the gripping member.

25 Figs. 17, 18 and 19, illustrate gripping members 45, 50 and 55, respectively, which are secured to the ends of the cylinders. Said members are slightly larger in diameter than the bearing surfaces of the head 2 30 which would normally rest upon the ground when the cylinder is standing on its end, thus providing a broad and firm base for supporting the cylinder in an erect position and embodying therewith the gripping members.

35 The gripping member 45, shown in Fig. 17, has an inwardly projecting flange 46 which forms the gripping member. Said flange 46 forms part of the cylindrical portion 47, which is secured to the end of the cylinder body 1.

40 The form of gripping member shown in Fig. 18, consists of a collar 50, which is shown secured upon a cylinder having a 45 convexed head 2. Said collar may be

slightly larger in diameter than the body of the cylinder, thus forming a substantial base for the cylinder, and the inwardly turned flange 52 upon the collar 50 forms the gripping member.

50 The gripping member 55, shown in Fig. 19, consists of a disk secured upon the bottom surface of the cylinder head. Said disk is provided with a central opening and the inner edge of the disk forms the gripping means.

55 The gripping members 45, 50 and 55 are shown provided with holes 48, 51, and 56, respectively, for the outlet of water, dirt or cinders which would otherwise accumulate within the gripping members.

Having thus described my invention I claim and desire to secure by Letters Patent;

1. A seamless drawn steel cylinder having a body portion and an integral drawn head closing one end of the cylinder, said head provided with a recess extending inwardly beyond the plane of the end of the body portion, and a handle secured upon said head located entirely within said recess.

60 2. A seamless drawn steel cylinder having a body portion and an integral drawn head closing one end of the cylinder, said head provided with a recess extending inwardly beyond the plane of the end of the body portion, and an annular member secured upon said head located entirely within said recess forming a handle for lifting the body portion.

75 3. A seamless drawn steel cylinder having a body portion with rounded end surfaces and an integral drawn head closing said body portion, said head having a concaved recess formed therein, a member having a curved surface adapted to be secured to said concaved surface of the head and said member having an inwardly projecting flange forming a handle for lifting the cylinder.

80 85 In testimony whereof I affix my signature.

JOSEPH A. STEINMETZ.
